UNITED STATES PATENT OFFICE.

ABNER B. SMITH AND HENRY J. GOFF, OF McCLOUD, CALIFORNIA, ASSIGNEES OF FORTY ONE-HUNDREDTHS TO FREDERICK E. SPENCER, OF McCLOUD, CALIFORNIA.

BUNDLE-TYING MACHINE.

1,197,773.

Specification of Letters Patent. Patented Sept. 12, 1916.

Application filed March 18, 1916. Serial No. 85,178.

To all whom it may concern:

Be it known that we, ABNER B. SMITH and HENRY J. GOFF, citizens of the United States, residing at McCloud, in the county of Siskiyou and State of California, have invented certain new and useful Improvements in Bundle-Tying Machines, of which the following is a specification, reference being had to the accompanying drawings.

- 10 This invention relates to certain improvements in bundle tying machines and is adapted for use more particularly with a machine of the particular character as set forth in our Patent No. 1,166,720 dated January 4, 1916, and it is an object of the invention to provide novel and improved means whereby the tying medium may be conveniently and expeditiously secured to the shaft of the twisting member.
- 20 The invention consists in the details of construction and in the combination and arrangement of the several parts of our improved tying machine whereby certain important advantages are attained and the device is rendered simpler, less expensive and otherwise more convenient and advantageous for use, all as will be hereinafter more fully set forth.

The novel features of the invention will 30 hereinafter be definitely claimed.

In order that our invention may be the better understood, we will now proceed to describe the same with reference to the accompanying drawings, wherein—

- 35 Figure 1 is a view partly in elevation and partly in section illustrating an embodiment of our invention in applied position; Fig. 2 is a view, detached, in perspective, of our improved wire holding device as herein set forth; and Fig. 3 is a fragmentary view in top plan of the shaft for the twister illustrating our invention as herein embodied applied thereto.

As disclosed in the accompanying drawings, 45 61 denotes an upright of predetermined height and having secured to its upper extremity the bearing block 62 through which is disposed the shaft 63 projecting beyond the opposite sides thereof, the outer extremity of said shaft 63 being operatively engaged with a suitable driving means, while the inner end of said shaft 63 has affixed thereto the twisting member 69 of a type

particularly described in our prior Patent No. 1,166,720 dated January 4, 1916.

76 denotes a cutting member arranged inwardly of the twisting member 69 and preferably of a character as described and illustrated in our prior patent hereinbefore referred to.

The periphery of the shaft 63 intermediate the block 62 and the cutter 76 is flattened, and resting upon said flattened portion is a plate 1 detachably held to the shaft 63 through the medium of the headed screw 2 directed through the shaft 63 and in threaded engagement with the plate 1 as indicated at 3. It is to be observed that the inner end of the plate 1 is provided with a lip or narrow extension 4 which extends within a corresponding recess formed at the inner end of the flattened portion of the shaft 63, whereby the plate 1 is held against swinging movement around the headed member 2.

The outer end of the plate 1 is provided with the upstanding flange 5 having its upper portion provided with a V-shaped recess 6, the edges of which being formed into knife edges so that an effective grip may be had upon the tying medium W which is 70 preferably a wire of predetermined gage.

The plate 1 inwardly of the flange 5 but in close proximity thereto is provided with the upstanding arch or loop 7 through which the free end of the tying medium W is 85 adapted to be threaded after it has been arranged within the recess 6 hereinbefore referred to. It will be perceived that the knife edges of the recess 6 will assure an effective engagement with the strand W and which 90 contact is further facilitated in view of the fact that the arch member or loop 7 has its upper portion arranged below the lowermost point of the recess 6.

From the foregoing description, it is 95 thought to be obvious that a tying machine constructed in accordance with our invention is of an extremely simple and comparatively inexpensive nature and is particularly well adapted for use by reason of the convenience and facility with which it may be assembled.

We claim:

1. In combination with a rotatable shaft provided with a twisting means, a plate 105 secured to the shaft to one side of the twist-

- ing means, said plate being provided with an upstanding flange having a recess in its outer margin, said plate being also provided with an arched member at a point inwardly 5 of the flange.
2. In combination with a rotatable shaft provided with a twisting means, a plate secured to the shaft to one side of the twisting means, said plate being provided with an 10 upstanding flange having a recess in its outer margin, said plate being also provided with an arched member at a point inwardly of the flange, said arched member being of such a height as to terminate inwardly of 15 the inner end of the recess of the flange.
3. In combination with a rotatable shaft provided with a twisting means, a plate secured to the shaft to one side of the twisting means, said plate being provided with 20 an upstanding flange having a recess in its outer margin, said plate being also provided with an arched member at a point inwardly of the flange, said recess being substantially V-shape in form.
4. In combination with a rotatable shaft 25 provided with a twisting means, a plate secured to the shaft to one side of the twisting means, said plate being provided with an upstanding flange having a recess in its outer margin, said plate being also provided 30 with an arched member at a point inwardly of the flange, the margins of the recess being formed into knife edges.
5. In combination with a rotatable shaft 35 provided with twisting means, an upstanding flange carried by the shaft to one side of the twisting means and provided with a recess in its outer margin, said shaft being also provided with an arched member spaced relatively to the flange.

In testimony whereof we hereunto affix our signatures in the presence of two witnesses.

ABNER B. SMITH.
HENRY J. GOFF.

Witnesses:

GUY E. EKWALL,
FLETCHER GREEN.
